ABSTRACT OF THE DISCLOSURE

A rotatable elbow tube is provided in the anolyte chamber of a chlor-alkali diaphragm cell for withdrawal of anolyte and ease in adjusting the hydrostatic head of anolyte which varies the pressure imposed on the diaphragm by the anolyte. A sight glass is provided which provides for rapid observation of the anolyte level. Also a sight glass is provided in the liquor withdrawal portion of the rotatable elbow tube for observing the anolyte being withdrawn and the flow rate of anolyte from the cell.

This invention relates to an anolyte liquid level control device for chlor-alkali cells and more particularly to an apparatus for the withdrawal of anolyte solution from a chlor-alkali diaphragm cell while maintaining a predetermined liquid level within the anolyte compartment.

It has recently been found to be desirable to operate a chlor-alkali diaphragm cell utilizing an anolyte recirculation method wherein brine feed solution is fed to the anolyte compartment of a chlor-alkali cell at a rate greater than that at which the feed solution flows through the diaphragm into the catholyte compartment. In the operation of the anolyte recirculation method, it is also desirable to maintain a certain liquid level within the anolyte compartment which level provides a hydrostatic head which brings pressure to bear upon the diaphragm thereby forcing liquid through the diaphragm. It is further desirable to be able to change the hydrostatic head within the anolyte compartment to provide for changes in operating procedures, thereby regulating the flow rate of anolyte liquor through the diaphragm into the catholyte compartment.

It is an object of the present invention to provide an apparatus for the withdrawal of excess brine feed solution from an anolyte compartment of a chlor-alkali cell diaphragm cell. Another object of the present invention is to provide an apparatus for the control of the liquid level within an anolyte compartment of such cells. These and other objects will become apparent to those skilled in the art from the description of the invention which follows.

In accordance with the invention there is provided an anolyte liquor withdrawal means for a chlor-alkali diaphragm cell comprising a passageway for liquids such as a tube, said passageway having an inlet means and an outlet means for liquids, said inlet means being positioned within the anolyte compartment of said cell and said outlet means being positioned external to the anolyte compartment of said cell, thereby providing for the removal of anolyte liquor from said anolyte compartment. In a preferred embodiment of the present invention, the described passageway is a curved tube or pipe capable of being moved, as by rotation, so as to raise and lower the inlet means within the anolyte compartment thereby regulating the anolyte liquid level.

The invention will be more readily described by reference to the drawings in which;

FIG. 1 is a partial sectional view of a chlor-alkali diaphragm cell showing the apparatus of the present invention located on the sidewall of the cell; and

2

FIG. 2 is a side elevational view of said apparatus.

The apparatus of the present invention is preferably mounted on a cell top 10 of a chlor-alkali cell in a position such that passageway tube 12 extends into the anolyte compartment 14 of said chlor-alkali cell. Tube 12 has liquid inlet means 16 and outlet means 18, the inlet means 16 regulating the anolyte liquid level 20 within the anolyte compartment 14 by withdrawal of liquid through tube 12 and the discharging of it from the cell through outlet means 18. The chlor-alkali cell has brine feed means 22 and chlorine withdrawal means 24 in communication with anolyte compartment 14. In the operation of the cell, brine is fed through brine feed means 22 into anolyte compartment 14 from whence it passes into the catholyte compartment 26 by passing through diaphragm 28. Cell liquor, brine containing sodium hydroxide, is withdrawn from the catholyte compartment by means of overflow pipe 25. In the operation of the anolyte recirculation method, the brine feed rate is greater than the rate at which the brine passes from the anolyte compartment 14 through the diaphragm 28 into the catholyte compartment 26. This excess brine is withdrawn from the anolyte compartment 14 by means of tube 12.

Tube 12 preferably has a bend or curvature therein equal to an arc of about 10 to 90 degrees. The curved configuration provides clearance for rotation of the tube about an axis passing through the center of cell wall hole 30 without causing tube 12 to strike the walls of the anolyte compartment. In this preferred embodiment, tube 12 can be rotated in a plane within the anolyte compartment, 90 degrees and more from the vertical. Thus, the anolyte liquid level 20 can be raised to within about a half-inch or so of the top of the anolyte compartment of the chlor-alkali cell and lowered to the level of cell wall hole 30. Such a change in anolyte liquid level 20 changes the hydrostatic pressure within the cell and effects the flow of liquid through diaphragm 28. Thus the flow of anolyte liquor through the diaphragm 28 can be regulated by changing anolyte liquid level 20. A higher liquid level 20 increases the hydrostatic pressure and, as such, increases the flow rate through the diaphragm.

Tube 12 is of a diameter sufficient to withdraw anolyte liquor at a rate approaching that at which brine is fed to the anolyte compartment. Since the brine is often fed to the anolyte compartment under pressure, and whereas the flow through tube 12 is primarily by means of gravity, the diameter of tube 12 is preferably about equal to or larger than brine feed means 22. Normally, tube 12 has an inside cross-sectional area equal to about 1 to 5 times the inside cross-sectional area of brine feed means 22. The preferred tube diameter use is preferably large enough to also vent gases through the tube while withdrawing liquid anolyte.

Tube 12 may be constructed of any material substantially inert to the conditions existing within the cell. Such conditions include operating temperatures within the range of about 90 to 110 degrees centigrade while submerged in a concentrated salt (NaCl) solution saturated with chlorine. In addition, such material of construction is preferably capable of withstanding chlorine attack at a pH in the range of about 1 to 7. Also, such materials are preferably electrically nonconductive to avoid loss of electrical current. It has been found, that various synthetic polymers such as polyvinylidene chloride, chlorinated polyvinyl chloride, chlorinated polyesters, chlorinated rubbers, and the like materials can be used. Glass and ceramic and various metals such as tantalum, titanium and the like can also be used as the passageway material.

As an aid to adjusting the liquid level 20 within the cell, there is preferably provided sight glass 31 which shows the anolyte level. Also, handle 32 is provided on

stem 34 of tube 12 to aid in rotating the tube when adjusting liquid level 20.

Outlet means 18 of tube 12, passes withdrawn anolyte liquor to withdrawal pipe 36. Withdrawal pipe 36 has sight glass 38 through which observations of the liquor being withdrawn from the anolyte compartment 14 and the flow rate thereof can be made.

As will be readily recognized by those skilled in the art, various modifications of the present apparatus can be made without departing from the spirit thereof. The particular shape and design of the tube can be changed to meet the particular shape and design of the tube can be changed to meet the particular cell requirements and to provide for various methods of changing the liquid level other than by rotating the tube. One such method which is readily apparent from the present disclosure is to provide means for the partial withdrawal of the tube from the anolyte compartment thereby lowering or raising the anolyte level as desired.

While there have been described various embodiments of the present invention, the apparatus described is not intended to be understood as limiting the scope of the invention, as it is realized that changes therein are possible. It is further intended that each element recited in any of the following claims is to be understood as referring to all equivalent elements for accomplishing substantially the same results in substantially the same or equivalent manner. It is intended to cover the invention broadly in whatever form its principles may be utilized.

What is claimed is:

1. In a chlor-alkali diaphragm cell comprising an anolyte compartment separated from a catholyte compartment by a porous diaphragm, said anolyte compartment comprising an anode, brine feed means and chlorine gas withdrawal means, the improvement which is an anolyte liquor withdrawal means comprising a passageway for the passage of anolyte having an inlet means capable of

being raised and lowered to change the liquid level within the anolyte compartment of said cell and an outlet means positioned external to the anolyte compartment of said cell thereby providing for the removal of anolyte liquor from said anolyte compartment.

5. 2. The apparatus of claim 1 wherein a sight glass means is positioned on said outlet means for the observation of liquid flow.

3. The apparatus of claim 1 wherein the passageway for liquids is a tube having a curvature therein equal to an arc of about 10 to 90 degrees, said curved tube having means for the rotation thereof in said anolyte compartment within a plane having an angle of up to about 90 degrees from the vertical, thereby raising and lowering the inlet means of said tube within said anolyte compartment.

10. 4. The apparatus of claim 1 wherein said passageway for liquids has gaseous venting means associated therewith.

15. 5. The apparatus of claim 3 wherein said passageway for liquids is of sufficient capacity to provide for the venting of gases while withdrawing said anolyte liquor.
